United States Patent

Des. 236,829
Patented Sept. 16, 1975

236,829

WATER PURIFICATION UNIT

William J. Berry, Jr., and William J. Berry III, Durham,
N.C., assignors to R & D Suppliers, Inc., Durham, N.C.

Filed Jan. 15, 1973, Ser. No. 323,806

Term of patent 14 years

Int. Cl. D23—01

U.S. Cl. D23—3

FIG. 3

FIG. 1

FIG. 2

FIG. 4

FIG. 1 is a front perspective view of a water purification unit showing our new design;

FIG. 2 is a right side elevational view thereof;

FIG. 3 is a top plan view thereof; and

FIG. 4 is a bottom plan view thereof.

The electric cord is broken away for convenience of illustration in FIGS. 1, 2, and 3, and omitted from FIG. 4.

We claim:

The ornamental design for a water purification unit, as shown and described.
